UNITED STATES PATENT OFFICE.

JAMES TARBOTTON ARMSTRONG AND AXEL ORLING, OF LONDON, ENGLAND.

ELECTROCAPILLARY APPARATUS.

No. 844,080.

Specification of Letters Patent.

Patented Feb. 12, 1907.

Application filed March 21, 1905. Serial No. 261,331.

To all whom it may concern:

Be it known that we, JAMES TARBOTTON ARMSTRONG, a subject of the King of England, and AXEL ORLING, a subject of the King of Sweden, both residing at London, England, have invented new and useful Improvements in and Relating to Electrocapillary Apparatus, of which the following is a specification.

This invention relates to electrocapillary apparatus, and has for its object the improvements hereinafter described with reference to the accompanying diagrammatic drawings, in which—

Figure 1 shows a vertical section through parts of an electrocapillary detector embodying our said improvements. Fig. 2 is a view illustrating our improved electrocapillary recorder; and Fig. 3 is a transverse section, on an enlarged scale, through the capillary end of the mercury-tube, illustrating a modification.

According to the construction shown in Fig. 1 we employ a U-shaped tube or vessel *b*, having a neck *g* of reduced diameter formed at the top of one of its legs. This vessel is supplied with a suitable quantity of mercury *e*, which occupies the bend at the bottom of the U and a suitable quantity of dilute sulfuric acid *d* or other suitable dissimilar fluid conductor, which occupies the upper part of the leg, provided with the neck *g*, the other leg being entered by a rod or equivalent part *k*, adapted to displace the mercury and to so adjust the height of the dilute acid *d* in the other leg. Into the neck, hereinbefore referred to, we introduce the capillary end *h* of a tube *f*, containing a column of mercury *e*, which is prevented from flowing by the capillary forces. The capillary end *h* of this tube *f* is of uniform diameter and is formed by drawing out a tube in the usual way; but the dimensions are such that the meniscus at the bottom of the column of mercury will be located at the top of the capillary portion *h* of the tube *f* when its surface tension is increased by a predetermined potential difference. The upper end of this tube, where its diameter is greater, is also entered by a rod or an analogous part *l*, adapted to displace some of the mercury in the tube, so as to vary the height of the column, and consequently its pressure and the position of the meniscus for the purpose of adjusting the latter. In practice the neck *g* is greased or otherwise treated, so as to

prevent its contents from wetting its walls, in order that creeping of the liquid may be prevented and that the surface tension of such liquid may, when desired, enable its upper surface to stand above the edge or lip *m* of the neck and there remain. The internal diameter of the neck *g* is a little larger than the external diameter of the capillary end *h* of the tube *f*, that enters it. By thus curtailing the surface of the dilute acid exposed to the air loss by evaporation is greatly reduced.

In fitting up the apparatus the capillary end *h* of the mercury-tube is first caused to enter the dilute acid *d*, and the height of the column of mercury in the tube *f* is then increased, by means of the displacer *l*, until its pressure causes the mercury to flow out from the capillary end *h*, and so drive out the air. The pressure is then decreased sufficiently to enable the capillary force to raise the column, which draws up dilute acid into the part from which the air was expelled. The positions of the meniscus and the surface of the dilute acid are now respectively adjusted by means of the displacers *k* *l*, hereinbefore referred to, so that the part of the capillary end of the tube traversed by the meniscus is above the top of the neck *g* of the vessel *b*. Terminals *i* *j* are fused into the mercury-tube *f* and into the U-shaped vessel *b*, respectively, so as to make a good electric contact with the liquid conductors contained by them. Preferably the capillary end of the mercury-tube is rendered opaque (see Fig. 3) except at parts *n*, diametrically opposite, where it is transparent, so as to permit the passage of a beam of light or other rays whose other dimension is varied by the position of the meniscus. It is also preferable that the lower part of the U-shaped vessel, which is occupied by the mercury, be provided with a constriction *o* for the purpose of hindering the movement of its fluid contents when the apparatus is subjected to vibration.

Instead of greasing the inner walls of the neck *g* of the acid-containing vessel *b* we may provide it with a removable edge or lip of wax or other material (not shown) so treated as to be non-wettable. The mercury-tube *f* is supported by an arm *p*, adapted to slide on a screw-threaded post *q*, upon which it may be adjusted by means of a nut *r*. The vessel *b* is similarly supported by an arm.

In Fig. 2 is shown an arrangement for photographically recording the movements of

the meniscus due to the changes of the actuating potential differences. According to this arrangement a beam of light or other suitable rays projected through an aperture ⁵ *t* in one of the walls *u* of a dark chamber is wholly or partly screened or diverted by the thread of mercury in the capillary end *h* of the tube *f* when the meniscus occupies certain positions. Behind the aperture *t* and ¹⁰ within the dark chamber a sensitized tape *v* or other surface is caused to travel, and it is upon this that a record in the shape of a band whose width is controlled by the position of the meniscus is photographically printed. ¹⁵ For this purpose we employ any suitable source *w* of light or other suitable rays having a reflector *x* and means, such as a lens *y* or its equivalent, of concentrating the rays upon a slit *z* in a screen 1. On the opposite side of ²⁰ the screen last referred to is located the capillary end of the mercury-tube in such a position that the movement of the mercury will intersect the beam of rays passing through the slit *z* in the screen 1 to a greater or less ²⁵ extent. An alum-bath 2 or equivalent means is preferably employed to screen out the heat-rays. One or more suitable lenses or their equivalents, such as are shown at ³⁰ 3 4 5, are employed to project an image of the displaced mercury through or upon the slot *t*, behind which the tape *v* is caused to travel by any well-known or suitable means. After the record has been made the sensitized surface is developed, fixed, and washed ³⁵ in the well-known manner. In some cases the recording device may be dispensed with and the image of the displaced mercury caused to fall upon a graduated or other surface, from which its movements may be observed, or, alternatively, a selenium-cell or ⁴⁰ its equivalent (not shown) may be employed and the movement of the displaced mercury caused to vary the illumination of the surface of such selenium-cell by the beam of light, whereby a local circuit, including a ⁴⁵ battery and a telephonic receiver or analogous part, may be actuated in the well-known manner.

What we claim as our invention, and desire to secure by Letters Patent, is—

⁵⁰ 1. An apparatus for observing or recording electrical phenomena consisting of a bent tube containing in one part mercury and in the other a conductor other than mercury, a capillary tube containing a liquid conductor ⁵⁵ and dipping into the end of the bent tube and means for passing an electric current through the tubes and the liquids therein.

⁶⁰ 2. In an apparatus for observing or recording electrical phenomena the combination with a capillary tube of a U-shaped tube having legs of unequal lengths, one end containing a conductor other than mercury and the remaining part of the U-shaped tube containing mercury.

⁶⁵ 3. In an apparatus for observing or recording electrical phenomena the combination with a capillary tube of a U-shaped tube containing mercury in one part and a conductor other than mercury in the other part and a level-regulating rod in the U-tube.

⁷⁰ 4. In apparatus for observing or recording electrical phenomena the combination of a capillary tube containing a liquid conductor with a level-regulating rod in the said tube ⁷⁵ and of a U-shaped tube containing a conductor other than mercury in one part and mercury in the other part.

⁷⁵ 5. In apparatus for observing or recording electrical phenomena the combination of a capillary tube containing a conducting liquid and a level-regulating rod dipping into the same with a U-shaped tube containing a conductor other than mercury in one part, mercury in the other part, and a level-regulating ⁸⁰ rod entering the open part of the U-shaped tube.

⁸⁵ 6. In an apparatus for observing or recording electrical phenomena the combination of a capillary tube with a U-shaped tube ⁹⁰ the curved part of the U-shaped tube being of constricted internal diameter.

⁹⁵ 7. In an apparatus for observing or recording electrical phenomena a U-shaped tube having a curved part of constricted internal diameter, one leg with a narrow end and a terminal leading into the tube.

¹⁰⁰ 8. In an apparatus for observing or recording electrical phenomena a U-shaped tube with a constricted curved portion combined with a level-regulating rod.

¹⁰⁵ 9. In an apparatus for observing or recording electrical phenomena a U-shaped tube having a restricted curved part combined with a reduced portion at the end of one leg ¹¹⁰ and a level-regulating rod entering the other leg.

¹¹⁵ 10. In an apparatus for observing or recording electrical phenomena a tube having a capillary part at one end and an open, wider, part at the other, fitted with a terminal and combined with a level-regulating rod entering the wide end of such tube.

¹²⁰ 11. An apparatus for observing or recording electrical phenomena consisting of a capillary tube containing a conducting liquid a bent tube containing mercury in one part and a conductor other than mercury in the other part, means for passing current through the conductors, a support for said tubes and means for adjusting the position of the tubes on the support.

¹²⁵ 12. An apparatus for observing or recording electrical phenomena consisting of a capillary tube containing a liquid conductor, a bent tube containing mercury in one part and a conductor other than mercury in the other part, means for passing current through the conductors, means for regulating the level of the conductors in the tubes, a ¹³⁰

support for the tubes and means for adjusting the tubes on the supports.

13. In an apparatus for observing or recording electrical phenomena a capillary tube 5 opaque at its end, and having transparent parts in the opaque end.

14. In an apparatus for observing or recording electrical phenomena a tube drawn out to capillary dimensions at its end, the capillary end being opaque and having transparent portions, and an electrically-operated column of liquid in said tube combined with a source of light deflected by the column of liquid.

15. In an apparatus for observing or recording electrical phenomena an opaque tube provided with a passage for light and an electrically-operated column of liquid adapted to move across the said passage.

In testimony whereof we have signed our names to this specification in the presence of two subscribing witnesses.
